UNITED STATES PATENT OFFICE.

ELMER R. CORWIN, OF CHICAGO, ILLINOIS, ASSIGNOR, BY MESNE ASSIGNMENTS, TO FRANK B. COOK COMPANY, OF CHICAGO, ILLINOIS, A CORPORATION OF ILLINOIS.

TELEPHONE-EXCHANGE SYSTEM.

1,109,164.

Specification of Letters Patent. Patented Sept. 1, 1914.

Application filed August 10, 1912. Serial No. 714,417.

To all whom it may concern:

Be it known that I, ELMER R. CORWIN, citizen of the United States, residing at Chicago, in the county of Cook and State 5 of Illinois, have invented a certain new and useful Improvement in Telephone-Exchange Systems, of which the following is a full, clear, concise, and exact description, reference being had to the accompanying drawings, forming a part of this specification.

My invention relates to telephone exchange systems and in its preferred embodiment includes much of the equipment disclosed in my co-pending applications Serial No. 15 714,415, filed August 10, 1912, and Serial No. 714,416, filed August 10, 1912, though the invention is not to be limited to the use of such equipment.

In practising my invention I preferably 20 employ selector switches, each common to a plurality of lines, for connecting calling lines with operators' responsive devices such as operators' telephones, there being link connectors at the exchange preferably adapted to their line joining function independently of these selector switches, though I do not limit myself to these characteristics in all embodiments of the invention. I make use of these selector switches not only for 25 the purpose stated but also in the process of extending calling lines into connection with called lines, the present embodiment of the invention including electro-magnetic switching mechanism for extending the ends 30 of the link connectors into connection with calling and called lines. I also desirably employ these selector switches for associating a suitable source or sources of ringing current with the link connectors thereby to 35 enable the called subscribers to be signaled. The signaling operation is desirably automatically or to some extent automatically performed and the disconnection of the ringing generator is also automatically effected when the called subscriber responds 40 and inasmuch as a selector switch which was employed to associate the operator's telephone with a calling subscriber remains in service for these purposes the operator's telephone would be out of commission during a 45 part of these operations when it might well be employed in association with another calling line, were it not for the apparatus and system forming the subject matter of the 50 present application. In order that the oper-

ator's telephone may be released after the operator has performed her part of the work in extending a calling line into connection with a called line, I provide switching mechanism which will transfer her telephone (or 55 other responsive device) from operative association with the selector switch which was initially employed into association with another selector switch so that her telephone may be used by another calling subscriber, this switching mechanism not interfering with the relationship which the first selector switch previously had with the link connector which was employed for connecting the calling and called subscribers. As the 60 invention is preferably employed there are two such selector switches for each operator's position and a switching device individual to each selector switch, each switching device being adapted to associate 65 the operator's telephone with the selector switch associated with such device and also to dissociate such telephone from such selector switch. Either of these switching devices is in that position in which the operator's telephone is associated with the corresponding selector switch while the other switching device is in such position as to dissociate the operator's telephone from the selector switch corresponding thereto so that 70 but one of these selector switches is set into operation when a call is initiated while the other selector switch is maintained in condition to have the operator's telephone transferred into association therewith when the 75 first selector switch to be employed has performed its function in enabling the operator to answer the calling subscriber and also to enable the operator to effect the connection of a link connector with the calling 80 and called lines and to initiate the establishment of connection between the ringing generator and the called line.

I will explain my invention more fully by reference to the accompanying drawings 85 in which—

Figures 1 and 2 taken collectively in their numerical order and with the conductors at the top thereof in alinement, represent a telephone exchange system equipped in accordance with the invention, and Fig. 3 is 90 a detail of construction.

In the drawings I have shown two telephone stations 120 and 190 whose lines extend to an exchange equipped in accordance 95

with the invention. Each station includes well known equipment comprising a telephone switch hook 1, a telephone receiver 2, a telephone transmitter 3, a signal bell 4, and a condenser 5. The telephone switch hook closes the bell bridge across the sides of its line when supporting the receiver, and closes the telephone bridge when the receiver is removed from the switch hook. Assuming that subscriber's station No. 120 desires communication with subscriber's station No. 190, the calling subscriber will remove his telephone receiver 2 from its switch hook 1 to open the bridge containing the signal bell 4 and condenser 5 and to close the metallically continuous bridge containing the telephone transmitter 3 and the telephone receiver 2. Circuit is thereupon established through the relay 6 which may be traced from the grounded terminal of this relay through its winding, the upper armature switch of ringing relay 7 and its normal contact (this relay being operated only when its line is a called line), the sides of the calling line, the lower armature switch of relay 7, and its normal contact, next to the uppermost armature switch of relay 8 and its contact, the relay 9, to the grounded battery 10, the battery 10 also supplying talking current to the transmitters. The relay 9 may be common to the lines of a group of subscribers' lines and when its armature is attracted a circuit is established which is traceable from the grounded battery 10 through the circuit interrupter 11, the armature of relay 9 and its contact, contacts of an operator's switch 9 when closed the lowermost armature switch of relay 12 and its normal contact, the motor magnet 13, to ground. The circuit of the motor magnet 13 is interrupted so that its armature moves the ratchet wheel 14 that carries wipers 15, 16, 17, 18 and 19 that pass over sets of waiting contacts belonging to the group of telephone lines having the relay 9, there being two sets of such waiting contacts indicated at 20, 21, 22, 23, and 24. When a subscriber initiates a call a circuit connection is established for the waiting contact 24 belonging to his line which circuit connection may be traced from the contact 24 of the calling line, the lowermost armature switch of relay 6 and its then engaged contact the follow-up contact of the armature switch immediately above the core of relay 8, the upper winding of the relay 8, to the grounded battery 10. That is potential is placed upon the waiting contact 24 of a calling line by connecting the grounded battery 10 therewith, the contacts 24 of non-calling lines being clear of such potential. When the wiper 19 engages the contact 24 having this potential the circuit connection just traced has a continuation that establishes a closed circuit which 65 continuation includes the wiper 19, the

follow-up normal contact of the upper armature switch of relay 12, the winding of relay 12, the contacts of an operator switch 9¹ when closed, the upper armature switch of relay 25 and one of its contacts, to ground. Thus the magnet 12 becomes energized and its upper armature switch leaves its normal follow-up contact into engagement with its alternate contact to establish a locking circuit through the magnet 12 and at the same time the lower armature switch of relay 12 is removed from its normal contact to open the circuit of motor magnet 13 whereby the wipers upon the actuated ratchet wheel 14 (the wipers 15 to 19 inclusive) are arrested. The locking circuit established by the magnet 12 may be traced from the grounded battery 10, the upper winding of relay 8, (the armature switch immediately above the core of this relay having left its normal follow-up contact and now engaging its alternate contact owing to the circuit initially established for this relay 8 at the lowermost armature switch of the previously energized relay 6), the armature switch immediately above the core of relay 8, the alternate contact of this armature switch, the waiting contact 21 of the operated wipers, the wiper 16 engaging this waiting contact, the upper armature switch of relay 12, contacts of an operator's switch 9¹ when closed, the upper armature switch of relay 25 and one of its normal contacts, to ground. The locking circuit for the upper winding of relay 8 continues through its armature switch immediately above its core, the alternate contact of this armature switch, both sides of the calling subscriber's line, the relay 6, to ground. One side of each telephone line is permanently connected with the talking waiting contact 21 and the other side of each subscriber's line is connected with the talking waiting contact 20 when next to the upper armature switch of relay 6 is attracted. Thus the talking waiting contacts 20 and 21 are connected with the talking wipers 15 and 16 respectively, whereby the operators' telephone conductors 26 are connected with the calling subscriber's line to include the operator's telephone or other responsive device 27 in circuit with the calling subscriber's line, the switch 9¹ being closed. The operator is now in telephonic communication with the calling subscriber, though it is to be understood that in practising all features of my invention I do not limit myself to the manner in which communication is established between calling subscribers and the operators. The selector switches herein shown are individual to the operators' positions, thereby being common to a plurality of lines. There are present means for electrically differentiating calling from non-calling lines whereby the selector switches individual to operators' positions 130

are arrested. That is in a calling line the lowermost contact 24 is connected with the lowermost armature switch of relay 6 with the results which have been described 5 whereas in non-calling lines the waiting contacts 24 remain disconnected.

Having ascertained the desired number the operator depresses a plunger 28 of a key associated with a connector switch that will 10 enter into the connection between the calling and desired lines. The operator next depresses the plunger 29 of a key or switch that will effect the connection of the calling line with one end of a link connector, the 15 other end of which is to be connected with the desired line by means of the connector switch governed by the switch having an actuated plunger 28. When the plunger 29 is depressed a circuit is established which 20 may be traced from the grounded upper armature switch of relay 25, the right hand contact of this switch, the contacts 30 closed by the operation of the key 29, contacts of switch 9¹ when closed, the actuated wiper 25 18, the waiting contact 23 engaged thereby, the lowermost armature switch of relay 8 and its then engaged contact, the lowermost armature switch of relay 31 and its then engaged contact, the winding of the motor 30 magnet 32 (belonging to the switch that is to connect the calling line with the talking 25 wipers 33, 34 at one end of a link connector 25, at whose other end the talking wipers 36 and 37 are located and which are to be 35 employed for connection with the waiting contacts of the desired line or line extension) the constantly operating interrupter 11 to the grounded battery 10. The motor magnet 32 now operates the ratchet wheel 39 to move the wipers 33, 34 and an extra wiper 40 around until the wiper 40 engages a grounded contact 41 whereupon the wipers 33, 34 and 40 are arrested with the first two 40 of these wipers in engagement with the waiting contacts 42 and 43 belonging to the calling line. Thus there is provided a calling line selector switch common to the telephone lines of a group. The contacts 41 pertaining to the telephone lines are grounded, when such lines are calling lines, by a path which is traceable from the grounded coil of relay 25, the intermediate armature switch of relay 25 and its normal follow-up contact, the left hand contacts of key 29, 45 contacts of key 9¹ when closed, the actuated wiper 17 belonging to the selector switch that was actuated by the calling subscriber when the call was initiated, the waiting contact 22 engaging this wiper, to the extra 50 waiting contact 41 individual to the calling line. This circuit portion, when engaging the wiper 40, is included in circuit with the upper armature switch of relay 31 and its normal follow-up contact, the winding of 55 this relay, the previously closed switch 44, and the grounded battery 10. The magnet 31 is thereupon energized to depress the wipers carried by the ratchet wheel 39 to 60 depress the wipers 33, 34 into engagement with the selected contacts 42 and 43, the magnet 31 in being energized causing its armature switches to be actuated, the circuit of the motor magnet 32 being opened at the lower armature switch of relay 31. The upper armature switch of this relay engages 65 its alternate contact before leaving its normal contact and thereby establishes a locking circuit for the relay which may be traceable from the grounded battery 10, the closed switch 44, the winding of relay 31, 70 the uppermost armature switch of this relay and its alternate contact, the wiper 34, the waiting contact 43 engaged by this wiper, the armature switches 7 of the calling line and their normal contacts together with 75 the calling line included between these armature switches, to the grounded winding of relay 6. The circuit which was previously traced through the relay 25 caused the energization of this relay and the establishment 80 of a circuit traceable from the grounded coil of the relay, its intermediate armature switch and the alternate contact of this armature switch, the previously closed switch 45, to the grounded battery 10. This circuit, which is a locking circuit for the relay 25, maintains the relay 25 energized thereby 85 to remove the upper armature switch of this relay from its contacts, ground being removed at the right hand contact of the upper armature switch of relay 25 to open the 90 circuit of motor magnet 32 to further guard against the re-operation of this motor magnet. When the wipers 33 and 34 have been 95 depressed into engagement with the contacts 42 and 43, a circuit is established traceable from the grounded battery 10 through the interrupter 11, the motor magnet 47 of a connector switch, the lowermost armature switch of relay 48¹, the next to the upper 100 strand of the link connector 35, the wiper 33, the waiting contact 42 then engaged thereby, the uppermost armature switch of 105 previously energized relay 6 of the calling line, to the grounded coil of this relay. The motor magnet 47 is then started into operation, the initial result being the closure of 110 the switch 48, a circuit being established when the wiper 50 engaged the waiting contact 51 of the called line and which circuit is traceable from the battery 49, the lowermost armature switch of relay 25, the left 115 hand contacts of switch 29, contacts of switch 9¹ when closed, the wiper 17, the waiting contact 22, the waiting contact 41, 120 the wiper 40 engaging the same, the lowermost strand of the link connector 35, the upper winding of relay 48¹, the extra wiper 50, the waiting contact 41 pertaining to the 125 called line, the lower intermediate armature 130

and the grounded battery 10. The magnet 31 is thereupon energized to depress the wipers carried by the ratchet wheel 39 to 60 depress the wipers 33, 34 into engagement with the selected contacts 42 and 43, the magnet 31 in being energized causing its armature switches to be actuated, the circuit of the motor magnet 32 being opened at the lower armature switch of relay 31. The upper armature switch of this relay engages 65 its alternate contact before leaving its normal contact and thereby establishes a locking circuit for the relay which may be traceable from the grounded battery 10, the closed switch 44, the winding of relay 31, 70 the uppermost armature switch of this relay and its alternate contact, the wiper 34, the waiting contact 43 engaged by this wiper, the armature switches 7 of the calling line and their normal contacts together with 75 the calling line included between these armature switches, to the grounded winding of relay 6. The circuit which was previously traced through the relay 25 caused the energization of this relay and the establishment 80 of a circuit traceable from the grounded coil of the relay, its intermediate armature switch and the alternate contact of this armature switch, the previously closed switch 45, to the grounded battery 10. This circuit, which is a locking circuit for the relay 25, maintains the relay 25 energized thereby 85 to remove the upper armature switch of this relay from its contacts, ground being removed at the right hand contact of the upper armature switch of relay 25 to open the 90 circuit of motor magnet 32 to further guard against the re-operation of this motor magnet. When the wipers 33 and 34 have been 95 depressed into engagement with the contacts 42 and 43, a circuit is established traceable from the grounded battery 10 through the interrupter 11, the motor magnet 47 of a connector switch, the lowermost armature switch of relay 48¹, the next to the upper 100 strand of the link connector 35, the wiper 33, the waiting contact 42 then engaged thereby, the uppermost armature switch of 105 previously energized relay 6 of the calling line, to the grounded coil of this relay. The motor magnet 47 is then started into operation, the initial result being the closure of 110 the switch 48, a circuit being established when the wiper 50 engaged the waiting contact 51 of the called line and which circuit is traceable from the battery 49, the lowermost armature switch of relay 25, the left 115 hand contacts of switch 29, contacts of switch 9¹ when closed, the wiper 17, the waiting contact 22, the waiting contact 41, 120 the wiper 40 engaging the same, the lowermost strand of the link connector 35, the upper winding of relay 48¹, the extra wiper 50, the waiting contact 41 pertaining to the 125 called line, the lower intermediate armature 130

switch of relay 8 of the called line and its follow-up contact, the lower winding of relay 8 of the called line, the contacts located beneath and closed by the actuated plunger 28, the winding of relay 52, to the battery 49, the key 28 being restored. The relay 48¹ is now energized to bring the wipers 36, 37 into engagement with the waiting contacts 53, 54 of the desired line.

10 When the relay 48¹ is energized a locking circuit is established therefor which is traceable from the grounded battery 10, the lower winding of relay 48¹, the upper armature switch of this relay, the lower intermediate 15 strand of the link connector 35, the wiper 34, the waiting contact 43, both sides of the calling line by way of the armature switches of ringing relay 7 and their normal contacts, to the grounded relay 6. The 20 circuit for the motor magnet 47 is opened at the lowermost armature switch or relay 48¹ so that this motor magnet discontinues its operation. Thus by means of the key 28 the range of operation of the connector switch 25 having the motor magnet 47 is determined so that its wipers are moved into co-operative relation with the waiting contacts of the called line. When the key 28 was depressed the horizontal limb of the switch lever 55 30 entered the notch of the key stem to hold said stem in a depressed position and thereby retain the contacts beneath the stem in engagement. When magnet 8 of the called line is energized a locking circuit is established 35 therethrough which may be traced from the grounded battery 10, the upper winding of relay 8, the armature switch immediately adjacent the core of this relay, the alternate contact of this armature switch, 40 the waiting contact 54 of the called line, the wiper 37 engaging the same, the companion wiper 34, the waiting contact 43 engaged by the wiper 34, both sides of the calling line, to the grounded relay 6 of the 45 calling line.

The foregoing description has been furnished with the assumption that either of the switches 9¹ is in a closed position while the other is in an opened position. As the 50 drawings show the system the upper switch 9¹ is in position to associate the operator's telephone 27 with the upper selector switch, while the lower switch 9¹ is in an open position to cut off association between the operator's telephone 27 and the lower selector switch. The upper selector switch will therefore be employed to associate the calling subscriber's telephone outfit 27 with the calling line having station 120. The control 55 of the electromagnetic devices having the motor magnets 32 and 47 for connecting link connectors with calling lines is effected, in the example chosen, through the intermediation of the upper armature switch 60 having the motor magnet 13 and the switch-

ing device 9¹ individual thereto. The calling and called lines having been connected as above described, the operator will, before releasing her upper key 9¹, depress her ringing key 56 that is individual to the employed 70 (the upper) selector switch to bring the ringing generator 57 into circuit connection with the called line to ring the signal bell 4 at the called station. In view of the circuit arrangement illustrated the ringing key 75 56 is to be depressed before the key 29 is depressed. The ringing generator 57 has a terminal contact 58 forming a part of each switch 56 that are individual to the different selectors. These contacts 58 are provided 80 with complementary contacts forming terminals of magnets 59 that are employed to maintain the generator 57 in circuit with the called lines until the called parties respond by removing their telephone receivers from 85 their switch hooks. When the selected key 56 has been depressed the spring pressed detent 60 (which was previously held against the stem of the key) enters the notch of the key so as to hold the key in its depressed 90 position. The releasing magnet 59 has its armature extended into association with the detent 60 so that when the magnet 59 is energized, as it is when the calling subscriber responds, the detent 60 is withdrawn 95 from the plunger notch of key 56 so that this key is restored to its normal position and the generator which was previously included in circuit at the contact 58 is excluded from circuit. The circuit over which current from 100 the generator finds path is traceable from the grounded terminal of the generator, the spring 58 of the actuated key 56 and the contact then engaged thereby, the winding of the holding magnet 59, an extra wiper 61 105 provided upon the corresponding selector switch, the waiting contact 62 then engaged by the wiper 61, the waiting contact 63, the wiper 64 then engaging the same, the upper strand of the link connector 35, the wiper 110 65, the waiting contact 66 then engaged thereby, and belonging to the called line, the upper armature switch of relay 7 and its alternate contact, the switch hook 1 at the called station, the signal bell 4 at the called 115 station, the condenser 5, the lower armature switch of relay 7 of the called line and its alternate contact, to ground, the relay 7 of the called line having been energized over a circuit traced from the grounded terminal 120 of this relay through the winding of the relay, the lower intermediate armature switch of relay 6 of the called line, the uppermost armature switch of relay 8 of the called line and its then engaged contact, the 125 interrupter 38, the battery 10, to ground. The bell bridges at the subscribers' stations are of such resistance as sufficiently to reduce the current flowing from the generator 57 to prevent the energization of the relay 130

59 thus included in circuit with the called subscriber's signal bell. When the called subscriber removed his telephone from its switch hook the low resistance telephone bridge at the called station is substituted for the comparatively high resistance bell bridge so that the current from the generator 57 is sufficiently increased, where it passes through the employed magnet 59, to energize this magnet and release the detent 60 from engagement with the notch in the plunger 56, whereby the circuit for the generator 57 is opened at the now elevated contact 58 of the employed key 56. By means of the interrupter 38 the relay 7 of the called line is intermittently energized so as intermittently to include the ringing generator 57 in circuit with the called subscriber's bell. If the called subscriber should happen to remove his telephone from its switch hook during a period when his relay 7 is deenergized the magnet 59 will be effectively energized to remove the generator 57 from circuit relation with the called line by reason of a circuit traceable from the grounded coil of relay 6, both sides of the called line by way of the armature switches of the called subscriber's relay 7 and their normal contacts, the armature switch immediately above the core of the called subscriber's relay 8 and its alternate contact, the upper winding of this relay 8, to the grounded battery 10, the called subscriber's relay 6 then closing a low resistance circuit for the magnet 59 which may be traced from the grounded uppermost switch of the called subscriber's relay 6 and the contact then engaged thereby, the waiting contact 66 of the called line, the wiper 65 then engaging the same, the wiper 64, the waiting contact 63 then engaged by the wiper 64, the waiting contact 62 of the employed selector switch, and the wiper 61 then engaging the same, the winding of magnet 59, the spring 58 of the actuated key 56 and its then engaged contact, to the grounded generator 57, the magnet 59 then operating to withdraw the detent 60 from engagement with the notch of the plunger of key 56 to open the generator circuit at 58. When the key 56 is restored the ground previously established at this lowermost switch spring 67 is removed from connection with the holding magnet 12 so that this holding magnet is deenergized to permit the wipers of the selector switch that previously associated the operator's telephone with the calling line to be restored to normal. All of the operations which have been described can be performed with the key 9¹ in either of its positions but inasmuch as it is desired to release the operator's telephone 27 after the operator has performed her work in connection with establishing the connection between calling and called lines, the upper key

9¹ is elevated to an open position after the key 28 is restored to normal whereupon the lower key 9¹ is shifted to that position in which the telephone outfit 27 is associated with the lower selector switch that may then serve to associate this telephone outfit with another calling line. The operator maintains supervision over the connection being established until the key 28 is restored the restoration of this key serving to indicate to the operator that the wanted line is idle. When the called subscriber responds and the signaling generator 57 has been excluded from circuit the selector switch initially employed to associate the operator's responsive device 27 with the calling line is restored to normal owing to the opening of the circuit for the holding magnet 12 belonging to this selector switch at 67. When the subscribers are through conversing they restore their receivers upon their switch hooks whereby circuits through the magnets 6 of these lines are interrupted at the switch hooks of the connected stations, the operative connections previously established at the armature switches of these relays 6 being broken whereby the apparatus is restored to normal, the magnets 31 and 48¹ releasing their associate ratchet wheels 39 and 48 to permit the wipers carried thereby to be restored to normal before the restoring movements of the upper armatures of these relays 31 and 48¹ have been completed, these relays 31 and 48¹, when energized, having disengaged the actuating pawls of their associate motor magnets from their corresponding ratchet wheels.

The keys 28 at an operator's position, there are more than those illustrated at each position, are provided with a magnet 52 common thereto and the armature of this magnet is common to all of the keys so that when any key of a group has been depressed it is associated by a common magnet 52. The switch levers 55, or in the instance shown the under switch lever 55, is serially related with the switch contacts beneath the switch plunger that is located above so that but one key 28 at an operator's position may, at one time, be brought into service. The keys 28 are brought into association with the lines by means of magnets 8 and the selector switches as illustrated.

Fig. 3 indicates a delaying device by which the ratchet wheel is permitted to restore to normal prior to the return of the actuating pawl of the motor magnet to the position in which it may actuate the ratchet wheel. A delaying detent *a* is pivoted at *b* and is pulled upon by a spring *c* so as to have a position to engage the pawl *d* of the motor magnet when this pawl is raised by the finger *e* operated by the holding magnet when energized. When the holding magnet is de-energized the finger *f* fixed upon the

ratchet wheel strikes the holding pawl *a*, when the ratchet wheel has reached normal, and released the holding pawl from engagement with the actuated pawl operated by 5 the motor magnet so that this actuated pawl may be restored to its relationship with the ratchet wheel.

It is desired to make cross references to my following co-pending applications: Serial 10 No. 709,405, filed July 15, 1912, Serial No. 709,406, filed July 15, 1912, and Serial No. 709,407, filed July 15, 1912, in which are broadly claimed operator controlled electromagnetic switches for establishing connection 15 between calling lines and calling line extensions or other telephone lines. By means of one of the systems disclosed in these co-pending applications calling line terminals are moved into connection with 20 contacts of link connectors; in another system direct connection is effected between contacts belonging to calling lines and contacts belonging to called lines; and in the remaining system contacts belonging to link 25 connectors are moved into connection with contacts belonging to the calling lines.

While I have herein shown and particularly described the preferred embodiment of my invention I do not wish to be limited to 30 the precise details of construction and circuit arrangement shown as changes may readily be made without departing from the spirit of my invention, but

Having thus described my invention I 35 claim as new and desire to secure by Letters Patent the following:

1. A telephone exchange system including lines extending from telephone stations to an exchange; a plurality of link connectors 40 at the exchange for uniting telephone lines; operators' responsive devices; a plurality of selector switches adapted to associate free operators' responsive devices with calling lines, the link connectors having operator 45 controlled means to adapt them to their line joining function independently of the aforesaid selector switches; operator controlled apparatus taking part in establishing connection between calling and called lines and 50 brought into operative association by the selector switches employed to connect operators' responsive devices with calling lines; and means for dissociating the operators' responsive devices from the selector 55 switches that have associated these responsive devices with calling lines and for transferring these responsive devices into association with other selector switches whereby the selector switches which were employed to associate operators' responsive devices with calling 60 lines may be continued in service to enable the operators to further connection between calling and called lines without interfering with the association of the op-

erators' responsive devices with other calling lines.

2. A telephone exchange system including lines extending from telephone stations to an exchange; a plurality of link connectors at the exchange for uniting telephone lines; operators' responsive devices; a plurality of selector switches common to a plurality of lines and adapted to associate free operators' responsive devices with calling lines, the link connectors having operator controlled means to adapt them to their line joining function independently of the aforesaid selector switches; operator controlled apparatus taking part in establishing connection between calling and called lines and 70 brought into operative association by the selector switches employed to connect operators' responsive devices with calling lines; and means for dissociating the operators' responsive devices from the selector switches 75 that have associated these responsive devices with calling lines and for transferring these responsive devices into association with other selector switches whereby the selector switches which were employed to associate operators' responsive devices with calling lines may be continued in service to enable the operators to further connection between calling and called lines without interfering with the association of the operators' responsive devices with other calling 80 lines.

3. A telephone exchange system including lines extending from telephone stations to an exchange; a plurality of link connectors 100 at the exchange for uniting telephone lines; operators' responsive devices; a plurality of selector switches adapted to associate free operators' responsive devices with calling lines, the link connectors having operator 105 controlled means to adapt them to their line joining function independently of the aforesaid selector switches; automatically operating calling line selector switches for connecting the link connectors with calling lines; operator controlled means for setting these line selector switches into operation and associated therewith by the selector switches employed for associating operators' responsive devices with calling lines; and means 110 for transferring the operators' responsive devices from the selector switches that have associated them with calling lines to association with other selector switches.

4. A telephone exchange system including lines extending from telephone stations to an exchange; a plurality of link connectors at the exchange for uniting telephone lines; operators' responsive devices; a plurality of selector switches adapted to associate free operators' responsive devices with calling lines, the link connectors having operator controlled means to adapt them to their line 120

joining function independently of the aforesaid selector switches; automatically operating called line selector switches for connecting the link connectors with called lines; operator controlled means for setting these line selector switches into operation and associated therewith by the selector switches employed for associating operators' responsive devices with calling lines; and means for transferring the operators' responsive devices from the selector switches that have associated them with calling lines to association with other selector switches.

5. A telephone exchange system including lines extending from telephone stations to an exchange; a plurality of link connectors at the exchange for uniting telephone lines; operators' responsive devices; a plurality of selector switches adapted to associate free 10 operators' responsive devices with calling lines, the link connectors having operator controlled means to adapt them to their line joining function independently of the aforesaid selector switches; a source of signaling current; means governed by the selector switches employed for associating operators' responsive devices with calling lines for associating the source of signaling current with called lines; and means for transferring the operators' responsive devices from the selector switches that have associated them with calling lines to association with other selector switches.

6. A telephone exchange system including lines extending from telephone stations to an exchange; a plurality of link connectors at the exchange for uniting telephone lines; operators' responsive devices; a plurality of selector switches common to a plurality of 15 lines adapted to associate free operators' responsive devices with calling lines, the link connectors having operator controlled means to adapt them to their line joining function independently of the aforesaid selector switches; automatically operating calling line selector switches for connecting the link connectors with calling lines; operator controlled means for setting these line selector switches into operation and associated therewith by the selector switches employed for associating operators' responsive devices with calling lines; and means for transferring the operators' responsive devices from the selector switches that have associated them with calling lines to association with other selector switches.

7. A telephone exchange system including lines extending from telephone stations to an exchange; a plurality of link connectors at the exchange for uniting telephone lines; operators' responsive devices; a plurality of selector switches common to a plurality of lines and adapted to associate free operators' responsive devices with calling lines, the

link connectors having operator controlled 65 means to adapt them to their line joining function independently of the aforesaid selector switches; automatically operating called line selector switches for connecting the link connectors with called lines; operator controlled means for setting these line selector switches into operation and associated therewith by the selector switches employed for associating operators' responsive devices with calling lines; and 75 means for transferring the operators' responsive devices from the selector switches that have associated them with calling lines to association with other selector switches.

8. A telephone exchange system including 80 lines extending from telephone stations to an exchange; a plurality of link connectors at the exchange for uniting telephone lines; operators' responsive devices; a plurality of selector switches common to a plurality of 85 lines and adapted to associate free operators' responsive devices with calling lines, the link connectors having operator controlled means to adapt them to their line joining function independently of the aforesaid selector switches; a source of signaling current; means governed by the selector switches employed for associating operators' responsive devices with calling lines for associating the source of signaling current 95 with called lines; and means for transferring the operators' responsive devices from the selector switches that have associated them with calling lines to association with other selector switches.

9. A telephone exchange system including lines extending from telephone stations to an exchange; a plurality of link connectors at the exchange for uniting telephone lines; operators responsive devices; a plurality of 105 selector switches adapted to associate free operators' responsive devices with calling lines, the link connectors having operator controlled means to adapt them to their line joining function independently of the aforesaid selector switches; and means for transferring the operators' responsive devices from association with employed selector switches into association with unemployed selector switches.

10. A telephone exchange system including lines extending from telephone stations to an exchange; a plurality of link connectors at the exchange for uniting telephone lines; operators' responsive devices; a plurality of selector switches common to a plurality of lines and adapted to associate free operators' responsive devices with calling lines, the link connectors having operator controlled means to adapt them to their line joining function independently of the aforesaid selector switches; and means for transferring the operators' responsive de-

vices from association with employed selector switches into association with unemployed selector switches.

11. A telephone exchange system including lines extending from telephone stations to an exchange; a plurality of link connectors at the exchange for uniting telephone lines; operators' responsive devices; a plurality of selector switches adapted to associate free operators' responsive devices with calling lines; operator controlled apparatus taking part in establishing connection between calling and called lines and brought into operative association by the selector switches employed to connect operators' responsive devices with calling lines; and means for dissociating the operators' responsive devices from the selector switches that have associated these responsive devices with calling lines and for transferring these responsive devices into association with other selector switches whereby the selector switches which were employed to associate operators' responsive devices with calling lines may be continued in service to enable the operators to further connection between calling and called lines without interfering with the association of the operators' responsive devices with other calling lines.
12. A telephone exchange system including lines extending from telephone stations to an exchange; a plurality of link connectors at the exchange for uniting telephone lines; operators' responsive devices; a plurality of selector switches common to a plurality of lines and adapted to associate free operators' responsive devices with calling lines; operator controlled apparatus taking part in establishing connection between calling and called lines and brought into operative association by the selector switches employed to connect operators' responsive devices with calling lines; and means for dissociating the operators' responsive devices from the selector switches that have associated these responsive devices with calling lines and for transferring these responsive devices into association with other selector switches whereby the selector switches which were employed to associate operators' responsive devices with calling lines may be continued in service to enable the operators to further connection between calling and called lines without interfering with the association of the operators' responsive devices with other calling lines.
13. A telephone exchange system including lines extending from telephone stations to an exchange; a plurality of link connectors at the exchange for uniting telephone lines; operators' responsive devices; a plurality of selector switches adapted to associate free operators' responsive devices with calling lines; automatically operating calling line selector switches for connecting

the link connectors with calling lines; operator controlled means for setting these line selector switches into operation and associated therewith by the selector switches employed for associating operators' responsive devices with calling lines; and means for transferring the operators' responsive devices from the selector switches that have associated them with calling lines to association with other selector switches.

14. A telephone exchange system including lines extending from telephone stations to an exchange; a plurality of link connectors at the exchange for uniting telephone lines; operators' responsive devices; a plurality of selector switches adapted to associate free operators' responsive devices with calling lines; automatically operating called line selector switches for connecting the link connectors with called lines; operator controlled means for setting these line selector switches into operation and associated therewith by the selector switches employed for associating operators' responsive devices with calling lines; and means for transferring the operators' responsive devices from the selector switches that have associated them with calling lines to association with other selector switches.

15. A telephone exchange system including lines extending from telephone stations to an exchange; a plurality of link connectors at the exchange for uniting telephone lines; operators' responsive devices; a plurality of selector switches adapted to associate free operators' responsive devices with calling lines; a source of signaling current; means governed by the selector switches employed for associating operators' responsive devices with calling lines for associating the source of signaling current with called lines; and means for transferring the operators' responsive devices from the selector switches that have associated them with calling lines to association with other selector switches.

16. A telephone exchange system including lines extending from telephone stations to an exchange; a plurality of link connectors at the exchange for uniting telephone lines; operators' responsive devices; a plurality of selector switches common to a plurality of lines adapted to associate free operators' responsive devices with calling lines; automatically operating calling line selector switches for connecting the link connectors with calling lines; operator controlled means for setting these line selector switches into operation and associated therewith by the selector switches employed for associating operators' responsive devices with calling lines; and means for transferring the operators' responsive devices from the selector switches that have associated them with calling lines to association with other selector switches.

17. A telephone exchange system including lines extending from telephone stations to an exchange; a plurality of link connectors at the exchange for uniting telephone lines; operators' responsive devices; a plurality of selector switches common to a plurality of lines and adapted to associate free operators' responsive devices with calling lines; automatically operating called line selector switches for connecting the link connectors with called lines; operator controlled means for setting these line selector switches into operation and associated therewith by the selector switches employed for associating operators' responsive devices with calling lines; and means for transferring the operators' responsive devices from the selector switches that have associated them with calling lines to association with other selector switches.
18. A telephone exchange system including lines extending from telephone stations to an exchange; a plurality of link connectors at the exchange for uniting telephone lines; operators' responsive devices; a plurality of selector switches common to a plurality of lines and adapted to associate free operators' responsive devices with calling lines; a source of signaling current; means governed by the selector switches employed for associating operators' responsive devices with calling lines for associating the source of signaling current with called lines; and means for transferring the operators' re-

sponsive devices from the selector switches that have associated them with calling lines to association with other selector switches. 35

19. A telephone exchange system including lines extending from telephone stations to an exchange; a plurality of link connectors at the exchange for uniting telephone lines; operators' responsive devices; a plurality of selector switches adapted to associate free operators' responsive devices with calling lines; and means for transferring the operators' responsive devices from association with employed selector switches into association with unemployed selector switches. 40 45

20. A telephone exchange system including lines extending from telephone stations to an exchange; a plurality of link connectors at the exchange for uniting telephone lines; operators' responsive devices; a plurality of selector switches common to a plurality of lines and adapted to associate free operators' responsive devices with calling lines; and means for transferring the operators' responsive devices from association with employed selector switches into association with un-employed selector switches. 50 55 60

In witness whereof, I hereunto subscribe my name this sixth day of August, A. D. 1912.

ELMER R. CORWIN.
